UNITED STATES PATENT OFFICE

2,601,813

SHAPER FOR LATHES

David G. Wallace, Chicago, Ill.; Arlie M. Wallace
administratrix of said David G. Wallace, deceased

Application March 31, 1947, Serial No. 738,339

2 Claims. (Cl. 90—39)

1

This invention relates to a shaper which derives its power from the spindle of a lathe with which it is combined, on which it is mounted.

An object of the invention is to provide a small shaper which can be applied to small lathes and, being compact, requires but little storage space when not in use.

Another object of the invention is to provide a shaper which may be mounted on a conventional lathe without changing the present parts of the lathe structure.

With the above and other objects and advantages in view, the invention consists of the novel details of construction, arrangement and combination of parts more fully hereinafter described, claimed and illustrated in the accompanying drawings in which:

Figure 1 is an elevational view of an embodiment of the invention in place on a conventional lathe;

Figure 2 is a sectional view on the line 2—2 of Figure 5;

Figure 3 is a front end view of the device;

Figure 4 is an elevational view partly in section of the work supporting table which is attached to the lathe bed;

Figure 5 is a top plan view of the device;

Figure 6 is a sectional view on the line 6—6 of Figure 1.

Fig. 7 is a sectional view similar to Fig. 2 with the arm moved 90° from the position it assumes in Fig. 2;

Fig. 8 is a sectional view similar to Figs. 2 and 7 with the arm moved 45° from the position it assumes in Fig. 7, such figures showing the various positions the face plate will assume during the operation of the device.

Referring more in detail to the drawings, the reference numeral 10 generally designates the shaper embodying the invention, which comprises the frame 11, which is mounted on the bed 12 of a lathe 13 by means of the inturned hook-like projection 14, and set screws 15 in the projections 14, when tightened, will retain the frame in fixed relation to the bed. The face plate 16 of the frame 11 is provided with a guide way 17 having bevelled edges 18 which cooperate with the bevelled edges 19 of the slide plate 20 and gib screws 21 in the face plate 16 are adjusted to compensate for wear between the plate 20 and the guide way 17 by bearing on the tapered wedge 26 inserted intermediate the plate 20 and guide way 17.

The central portion of face plate within the guide way 17 is cut out as at 22, and guide bars

2

23 are secured to the slide 20 by means of fasteners 24 which pass through the cut out to enter the slide 20 at the rear thereof. The bars 23 are provided with spaced apertures 25 for adjustment of the bars by the insertion of the fasteners 24 in the spaced apertures 25.

Slidably mounted between the bars 23 is the block 27 which loosely carries the pin 28 having the threaded end 29 on which is mounted the 10 nut and washer 30 and 31 respectively. Intermediate the mounting end and threaded end 29, the pin 28 has an oval shaped portion 32 which is receivable in the elliptical shaped slot 33 in the arm 34, and a screw 35 entering the arm 32 15 passes into the portion 32 to be received in the seat 36 in one end of the slot 33. The screw 35 has the reduced end 37 comparing in size to the seat 36, and a pin 38 engaging the groove 39 in the head of the screw retains this screw from in 20 and out movement to cause the arm 34 to be adjusted with relation to the portion 32 of the pin 28.

Secured to the opposite end of the arm 34 by a pin 40 is a short shaft 41 which has the tapered 25 sleeve 42 secured thereto by a pin 43, and this sleeve coacts with the spindle of the head stock 44 of the lathe 13 to cause the arm 34 to oscillate the slide 20 in the guide way 17.

The slide 20 has a forwardly right angularly extending mounting arm 45 which has the clapper box 46 secured thereto by fasteners 47. The box 46 carries the tool post 48 for mounting the tool 49, the clapper box being adjusted vertically by means of the feed screw 50, such adjustment being gauged by the hand gauge 51 coacting with the screw 50.

A work holder 52 comprising the lower plate 53 is secured to the lathe tool carriage 54 by a bevelled slot 55 engaging the similarly bevelled trackway 56 of the carriage 54, and gib screws 57 are 40 adjusted to compensate for wear between the sliding surfaces of the holder 52 and trackway 56.

The plate 53 is provided with a longitudinal T-shaped slot 58 which carries the similar shaped 45 nut member 59 which receives the screw bolt 60 to secure the guide 61 in the transverse feedways 62 in the plate 53. The guide 61 carries the set screws 63 for engaging a piece of work between the guide 61 and guide 64 which is mounted in 50 a guideway 65 at the far end of the plate 53.

The shaper previously described is light in weight, compact and can be attached to any type of conventional lathe without altering the construction of the lathe.

55 In use and operation, the frame 11 is mounted

on the bed lathe as previously described. The sleeve 42 is mounted on the spindle of the lathe and the arm 34 transmits the rotary motion of the spindle into an oscillating or reciprocating motion. Such motion being accomplished in the following manner. The shaft 41 acting as a fixed pivot for the arm 34 will cause the rotation of the arm on the pivot. The pin 32 rotatably receiving the block 27 permits the block to rotate freely on the pin. As the arm rotates the block slides between the bars 23 until it is urged sideways in one direction by the rotation of the arm 34. The block engaging the bars will cause the plate 20 to which the bars 23 are fixed to reciprocate as set forth. It is believed that a comparison of this operation with Fig. 2 will clearly set forth the operation of the reciprocation of the plate 20 and the operation of the device. The desired tool is mounted in the post 48, and the work is mounted on the holder 52. The tool is adjusted by the feed screw 50, so that the tool may engage the work.

Thus rotation of the spindle causes the slide 20 to reciprocate back and forth, the tool being adjusted as the work progresses by the screw 50.

The shaper is easily mounted on the lathe and it is easily removed, and it is believed that the shaper will accomplish the objects of the invention.

From the foregoing description, the operation and structure of the invention will be apparent to those skilled in the art, and it is to be understood, that changes in the minor details of construction, arrangement and combination of parts

may be resorted to, provided they fall within the spirit of the invention and the scope of the appended claims.

Having thus described the invention, what is claimed as new and desired to be secured by Letters Patent is:

1. A planer attachment, for use with a lathe having a bed, a driven spindle and a tool carriage, said device comprising the combination of a supporting frame for mounting on said bed, a transverse guide way in said frame, a slide plate mounted in said guide way, guide bars mounted on the rear of said slide plate, a block slidably mounted intermediate of said bars and means connected to said block and said spindle for transmitting the rotary motion of said spindle to reciprocating motion for movement of said slide plate.

2. The invention as in claim 1 wherein means is provided for securing said frame to said bed and said means attached to said spindle is adjustable with relation to said slide plate.

DAVID G. WALLACE.
